Primary Examiner — Karen E Eldridge Powers(74) Attorney, Agent, or Firm — DLA Piper LLP USCLAIM

The ornamental design for a bra, as shown and described.

DESCRIPTION

FIG. 1 is a perspective view thereof, according to an embodiment of the claimed design;

FIG. 2 is a front elevation view thereof;

FIG. 3 is a back elevation view thereof;

FIG. 4 is a left side elevation view thereof;

FIG. 5 is a right side view thereof;

FIG. 6 is a top plan view thereof; and,

FIG. 7 is a bottom plan view thereof.

The broken lines in the drawings illustrate those features of the article to which the design is applied that form no part of the claim.
